(57) **CLAIM**

The ornamental design for a wasp trap, as shown and described.

DESCRIPTION

FIG. 1 is a first perspective view of a wasp trap showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the wasp trap thereof;

FIG. 10 is another exploded view of the wasp trap thereof; and,

FIG. 11 is an enlarged view of the selected portion 11 in FIG. 1.

The broken lines shown in the drawings depict portions of the wasp trap that form no part of the claimed design.
